UNITED STATES PATENT OFFICE.

LEOPOLDO CORDOVA, HIJO, OF MOBILE, ALABAMA.

GRATE AND FIREPLACE ATTACHMENT.

1,284,603.

Specification of Letters Patent. Patented Nov. 12, 1918.

Application filed May 9, 1918. Serial No. 233,451.

To all whom it may concern:

Be it known that I, LEOPOLDO CORDOVA, Hijo, a citizen of the Republic of Honduras, residing at Mobile, in the county of Mobile 5 and State of Alabama, have invented new and useful Improvements in Grate and Fireplace Attachments, of which the following is a specification.

This invention relates to improvements in fireplace grates and particularly to heat radiating attachments for grates of this class, and the primary object of the invention is to attain the maximum heat from the fires in grates and open fireplaces and also to provide for regulating the heat through the medium of a novel and efficient draft system and circulation of the products of combustion through a drum or radiator forming part of the attachment. A further object 20 of the invention is to provide a simple and effective construction of fireplace casing and face plate and radiator or drum attachment capable of being readily applied in operative position in any ordinary form of fireplace 25 and standard make of grate without requiring a particularly special or expensive preparation or reorganization of the grate structure and fireplace to receive the components of the improved attachment. A still further object of the invention is to provide a heat regulating and radiating attachment for ready disposition in a fireplace over an ordinary basket grate that will operate and serve to economize in the use of fuel with 30 a materially increased amount of radiated heat proportionate to the fuel used within a room or compartment into which a radiating or drum portion of the attachment projects.

With these and other objects and advantages in view, the invention consists in the construction and arrangement of the several parts which will be more fully hereinafter described and claimed.

45 In the drawings:

Figure 1 is a front elevation of a portion of a fireplace and the improved attachment disposed therein.

Fig. 2 is a rear side elevation of the attachment.

Fig. 3 is a longitudinal vertical section taken in the plane of the line 3—3, Fig. 1.

Fig. 4 is a horizontal section taken in the plane of the line 4—4, Fig. 3.

55 The numeral 5 indicates the fireplace having the usual top flue 6 leading into a chim-

ney or other exit or outlet. At a suitable elevation within the fireplace, a basket grate 7 is mounted and provided with the usual upper front rail 8.

The improved attachment comprises a face or cover plate 9 carrying a rearwardly projecting casing 10 fully open at the bottom, at 11, and having an upper outlet opening 12 formed in an upwardly and forwardly inclined dome or cap 13. The casing 10 is suitably secured to the face or cover plate 9 and the lower edge thereof rests upon and is supported by the rail 8 of the grate 7. In the face or cover plate 9 an enlarged circular opening 14 is formed at a predetermined and preferred elevation above the rail 8 of the grate 7, and around this opening is an outer flange 15 over which is movably fitted the inner extremity of an inclosed 70 radiator or drum 16 having material projection outwardly from the said face or cover plate. The radiator or drum 16 is preferably of the shape in end elevation and vertical and horizontal section as respectively shown by Figs. 1, 3 and 4, and at one side of the center has upper and lower hinge straps 17 which coöperate with hinge straps 18 secured to the face or cover plate, both sets of straps 17 and 18 having knuckles 19 75 through which a pintle rod 20 extends to provide means for readily swinging the radiator or drum 16 into closed and open position as may be required. At a suitable elevation a horizontal partition or baffle 90 plate 21 is mounted in the casing 10, said partition or baffle plate having extremities 22 projecting forwardly through the opening 14 at opposite sides of a central arcuate recess 23, as clearly shown by Fig. 4, the 95 extremities 22 providing supporting ledges for a purpose which will be presently explained. The arcuate recess 23 in the partition or baffle plate 21 provides a feed opening over the grate 7 and whereby fuel may 100 be readily supplied to the grate through the opening 14. The radiator or drum 16 also has a fixed horizontal partition or baffle plate 24 secured therein and projecting through the rear end thereof far enough 105 to extend over and partially cover the partition or baffle plate 21 and particularly the recess or feed opening 23 in said latter partition. The partition or baffle 24 extends only partially forwardly through the length 110 of the radiator or drum 16 so as to provide an unobstructed flue 25 within the outer end

of the said radiator, the outer end of the radiator being preferably curved. The partitions or baffle plates 24 and 21 are so disposed relatively to each other that the rear 5 portion of the partition or baffle plate 24 will slide over and closely contact with the partition or baffle plate 21 when the radiator is closed, and when the radiator is opened the rear portion of the partition or baffle 10 plate 24 easily moves off the partition or baffle plate 21 and clears the recess or opening 23 to an extent equal to the degree of opening of the said radiator or drum, as indicated by dotted lines in Fig. 4. When 15 the radiator is closed, as shown by Figs. 1 and 4 in full lines, the recess or opening 23 is shut off, and the only medium of communication between the basket grate and the outlet flue 6 is outwardly through the 20 radiator or drum 16 beneath the partition or baffle plate 24 and then over the end of the latter through the flue 25 at the inner or front end of the radiator or drum and then rearwardly through the radiator or drum 25 over the said partition or baffle plate 24 and into the upper part of the casing 10 and out through the opening 12 into the said flue 6. By means of the circulation of the products 30 of combustion through the radiator or drum, the latter becomes heated and materially increases the heat of the room or compartment into which it projects from the fireplace, the up-draft created by the flue 6 causing the products of combustion to regularly move 35 through the drum or to take the course just explained.

Beneath the basket grate 7 an ash-pit 26 is provided, the face or cover plate 9 extending downwardly over this pit or fully to 40 the hearth 27 of the fireplace, as clearly shown by Fig. 3. The ash-pit is rendered accessible by a lower hinged door 28, and above this door a series of openings 29 are formed in the plate 9, a suitably apertured 45 slide or damper plate 30 coöperating with the series of openings 29 to regulate the draft or the inflow of the air beneath the grate. It is also obvious that, under certain conditions, when an increased draft may be 50 desired, the lower door 28 may be opened to any degree. The improved attachment also includes means for agitating the coal and removing the ashes and collected cinders in the grate and consists of a rocking rod 55 31 held in suitable bearings 32 at the inner side of the plate 9 just above the draft openings 29, as clearly shown by Fig. 2. A handle or oscillator 33 is connected to the rod 31 and movably extends through a slot 34 in 60 the plate 9. Connected to the rod are a plurality of rearwardly projecting arms 35 having upturned extremities 36 with T-heads 37, said heads being so positioned as to readily move upwardly and downwardly 65 between the bars of the grate. This agitat-

ing attachment may be readily brought into operation through the medium of the handle 33 and moved upwardly so that the T-heads 37 on the upturned extremities 36 of the arms 35 may be brought into engagement with the burning coal within the grate and relieve the same from ash or other accumulations which will fall into the ash-pit 26 below. When this agitating means is not in use, it will occupy the position as shown 70 in dotted lines by Fig. 3. This agitating means provides for keeping the grate clear and permitting the draft air from beneath the grate to readily pass through the burning coal and then outwardly through the 75 radiator or drum 16 for effectively heating the latter.

The main advantage of the improved attachment is that it may be readily applied to and within a fireplace and coöperate with 80 a basket grate to provide an effective heating means. At any time desired the grate may be replenished with fuel or coal by opening the radiator or drum 16 which has a frictional jointure with relation to the flange 85 15 to provide an air-tight connection. The comparative simplicity of the improved attachment will materially reduce the cost of manufacture thereof, and, moreover, the improved attachment may be readily set up or 90 applied in operative position over a fireplace or grate without requiring any great amount of mechanical knowledge. It will be understood that the proportions and general dimensions of the several parts of the 95 improved attachment may be varied to adapt the same for application to fireplace openings of different sizes and over grates of large and small capacity.

I claim as my invention:

1. A grate and fire-place attachment of the class specified, comprising a fire-place face plate and a casing to engage in the fire-place, the casing having an open bottom to fit on the grate and a top outlet opening 105 and also provided with an intermediate fixed horizontal baffle plate with a front edge recess to permit fuel to pass therethrough, and a radiator hinged to the face plate to close over a portion of the latter plate and casing 110 and also having a fixed horizontal baffle plate extending partially into and through the length thereof and movable therewith, said baffle plate of the radiator projecting beyond 115 the rear end thereof to closely slide over the baffle plate of the casing and to open and close the recess in the said casing baffle plate.

2. A grate and fire-place attachment of the class specified, comprising a fire-place face plate and casing to engage in the fire- 120 place and having an open bottom and a top outlet opening, the casing also having an intermediate partition fixed therein and provided with a recess in its front edge, and a radiator movably secured to the face plate 125 130

- and casing and provided with a horizontal baffle fixed therein and projecting rearwardly therefrom to move through the face plate into the casing and to closely slide over 5 the top surface of the baffle plate of the casing and open and close the recess of said latter baffle plate, the baffle plate in the radiator extending only partially toward the outer end of said radiator and horizontally dividing the latter.
- 10 3. A grate and fire-place attachment of the class specified, comprising a fire-place casing to engage in the fire-place and having an open bottom to fit over a grate and a top outlet for escape of products of combustion, the casing also having an intermediate fixed baffle plate with a recess in its front edge, a face plate to which the casing is secured, said face plate having an opening therein 15 adjacent to said baffle plate of the casing to expose the baffle plate through the casing, and a radiator movably secured to the face plate over the said opening and also provided with a horizontal baffle fixed therein 20 and projecting rearwardly to closely slide and engage over the top surface of the baffle plate of the casing to close and open the recess in said casing baffle plate, the face plate, casing and dome being applicable as a unit 25 to the fire-place.
- 30 4. A grate and fire-place attachment of the class specified, comprising a fire-place casing to engage in the fire-place and having an open bottom to fit over a grate and a top outlet opening for escape of products of combustion, the casing also having an intermediate horizontal fixed baffle plate dividing the same and formed with a recess in its front edge and front ledge projections at opposite 35 sides of the recess, a face plate to which 40
- the casing is secured, said face plate having an opening therethrough adjacent to and exposing said baffle plate of the casing, and a radiator movably secured to the face plate at one side thereof to swing laterally and 45 provided with a fixed horizontal baffle plate therein projecting beyond the rear end thereof to closely slide and engage over and open and close the recess of the casing baffle plate and also to engage the said ledges. 50
5. A grate and fire-place attachment of the class specified, comprising a fire-place casing to engage in the fire-place and having an open bottom to fit over a grate and an upper outlet for escape of products of combustion, the casing also having an intermediate fixed baffle plate dividing the same and provided with a recess in its front edge, a face plate to which the casing is secured, said face plate having an opening therein adjacent to said baffle plate of the casing, the said face plate having a lower hinged door and a plurality of draft openings above the door controlled by a slide damper, and a radiator movably applied over the opening 65 in the face plate and hinged at one side to said latter plate and provided with a horizontal baffle fixed therein and projecting rearwardly from the rear edge thereof to pass through the face plate and closely slide 70 and engage over and open and close the recess of the casing baffle plate.

In testimony whereof I have hereunto set my hand in presence of two subscribing witnesses.

LEOPOLDO CORDOVA, Hijo.
